UNITED STATES PATENT OFFICE.

HIRAM MAINE, OF INDIANAPOLIS, INDIANA.

SNOW-REMOVING APPARATUS.

No. 813,050.

Specification of Letters Patent.

Patented Feb. 20, 1906.

Application filed December 18, 1905. Serial No. 292,222.

To all whom it may concern:

Be it known that I, HIRAM MAINE, a citizen of the United States, residing at Indianapolis, in the county of Marion and State of Indiana, have invented new and useful Improvements in Snow-Removing Apparatus; and I do declare the following to be a full, clear, and exact description of the invention, reference being had to the accompanying drawings, and to the letters of reference marked thereon, which form a part of this specification.

This invention relates to apparatus for removing snow from streets to manholes of sewers, and it has reference particularly to a sliding conveyer for scraping and receiving the snow from the streets and conveying the snow to a manhole, to an unloader, and to a manhole-guard attachable to the manhole-top for guiding the snow into the manhole.

Objects of the invention are to provide apparatus whereby snow may be expeditiously and economically removed from the streets of towns and cities and dumped into sewers, incidentally avoiding the expense of shoveling the snow onto wagons or sleds, and to provide snow-removers that may be employed for various other purposes.

With the above-mentioned and minor objects in view the invention consists in a conveyer provided with an unloader, draft appliances connected to the unloader and detachably connected to the main part of the conveyer, and a manhole-guard adapted to stop and hold the conveyer while the unloader operates; and the invention consists, further, in the novel parts and the combinations and arrangements of parts, as hereininafter particularly described and claimed.

Referring to the drawings, Figure 1 is a perspective view of the conveyer with its unloader and draft appliances connected therewith, parts being broken away; Fig. 2, a longitudinal central vertical sectional view showing the complete apparatus, as when unloading snow from the conveyer to a manhole, the manhole-guard being in position at a manhole; and Fig. 3, a perspective view of the manhole-guard.

In practically carrying out the invention a suitable conveyer is provided, the main part of which has a scoop-like appearance and comprises a flat bottom A, having a scraping end a and adapted to slide on a street or roadway, a pair of upright sides B and B', attached to the bottom and provided with lon-

gitudinal guides b and b', and a tail end C. The guides are attached to the top of the sides, but may be arranged elsewhere on the sides. The forward ends of the sides B and B' of the conveyer have studs D and D' attached thereto for draft purposes, any suitable form of which may be provided. A guiding-handle E is attached to the rear end of the conveyer.

The unloader comprises a suitable tail board or plate F, that normally rests on the bottom A and against the tail end C and is movable to the forward end of the main part of the conveyer, being suitably arranged to slide on the floor A and to be guided by the longitudinal guides to prevent its rising from the bottom A. The tail board or plate may be one of various suitable shapes, so that it may be kept approximately upright while in operation away from the tail end C while pushing the snow out of the main part of the conveyer.

A pair of shafts G and G', having a swing-tree c, are provided with a pair of coupling-irons H and H', preferably formed as hooks and having each an eye d, the hooks being attachable to and detachable from the studs D and D', being normally connected to the studs. A pair of links I and I', which may consist of either ropes or chains, are connected to the eyes of the coupling-irons and extend longitudinally along the inner sides of the sides of the main part of the conveyer to the tail-board F, to which they are connected by means of hooks e and e', that are attached to the links, and eyes f and f', that are attached to the tail-board and receive the hooks. The links, however, may be otherwise connected to the tail-board. The shafts may be modified, obviously, so that two or more draft-horses may be employed.

A guard for the sewer-manholes comprises a bottom J, having a hole g therein, a number of guide-bars h, attached to the bottom J adjacent to the hole g and designed to enter a manhole and hold the guard securely in place thereat, a stop-bar K, secured to the bottom, at the front thereof, and having lips j and j' extending upwardly and forwardly, and a deflector L, attached to the bottom J and standing upright about the hole g, with an open front.

In practical use a sewer-manhole i is to be uncovered, and the guide-bars h are to be inserted therein, so that the bottom J of the guard may rest upon the top of the wall of

the manhole. The conveyer and its parts are to be arranged as indicated in Fig. 1, and a horse or horses are to be suitably hitched to the draft appliances. A driver may guide 5 the conveyer by the handle E, if necessary, while the conveyer may be drawn on the ground or street-pavement, so that the snow may be gathered or be scraped or scooped into the conveyer as it is drawn toward the manhole. When arriving, the end a is to be drawn under the lips j and j' against the stop-bar K. Then the coupling-irons H and H' are to be disconnected from the studs D D' or similar lugs that may be employed, and the draft will then be applied to the tail-board F, so as to force the snow out of the main 15 part of the conveyer against the deflector L and into the manhole. The tail-board may then be replaced in its normal position and 20 the coupling-irons connected to the studs or lugs, after which another load may be obtained, as before, and dumped in the same manner.

Having thus described the invention, what 25 is claimed as new is—

1. A snow-remover including a conveyer for gathering and hauling snow and provided with an unloader movable therein.

2. A snow-remover including a conveyer for gathering and hauling snow and provided 30 with an unloader movable to draw the snow therefrom, and draft appliances attached to the conveyer-body and to the unloader part thereof.

3. A snow-remover including a sliding conveyer provided with draft appliances, and a guard for manholes of sewers provided with a plurality of guide-bars insertible into a manhole and having an upright deflector. 35

4. A snow-remover including a conveyer 40 comprising a main part having a bottom, sides provided with guides, a tail end, a handle at the tail end, and draft-lugs at the forward ends of the sides; an unloader comprising a tail-board movable on the bottom of the 45 main part in connection with the guides, and draft appliances having coupling-irons attachable to the draft-lugs and provided with links connected with the tail-board.

In testimony whereof I affix my signature 50 in presence of two witnesses.

HIRAM MAINE.
